U.S. Appl. No. 29/377,388, Coffman et al., "Graphical User Interface for a Display Screen or Portion Thereof," filed Oct. 20, 2010.

Primary Examiner — Karen E Kearney

(74) Attorney, Agent, or Firm — Sterne, Kessler, Goldstein & Fox PLLC

CLAIM

The ornamental design for a display screen or portion thereof with graphical user interface, as shown and described.

DESCRIPTION

The FIGURE is a front view of a display screen or portion thereof with graphical user interface showing our new design. The broken lines surrounding the FIGURE show a display screen or portion thereof and form no part of the claimed design. The dot-dash lines within the FIGURE show an unclaimed boundary and the area within forms no part of the claimed design.
